(57) CLAIM

The ornamental design of the door edge with cover strip, as shown and described.

DESCRIPTION

FIG. 1 is a perspective view of a first exemplary embodiment of the door edge with cover strip showing our new design;

FIG. 2 is a front view of the door edge with cover strip of FIG. 1;

FIG. 3 is a perspective view of a second exemplary embodiment of the door edge with cover strip showing our new design; and,

FIG. 4 is a front view of the door edge with cover strip of FIG. 3.

The broken lines are provided for illustrative purposes only, and form no part of the claimed design. In addition, the portions of the door that are not shown in the drawing do not form any part of the claimed design. Further, the full lines shown in the drawing views merely illustrate the surfaces of the design which are being claimed therein.
